INVENTOR

INVENTOR
Edward A. Thielen.
BY
Albert Edelstein
ATTORNEY

UNITED STATES PATENT OFFICE.

EDWARD ADAM THIelen, OF DORRANCE, KANSAS.

HOIST.

Application filed March 8, 1927. Serial No. 173,736.

The invention has for its object to provide certain new and useful improvements in hoists of the type disclosed in my Patent #1,599,690, issued September 14, 1926, and which provide for greater ease of use and adaptability of the hoist to its intended purpose in lifting automobiles and automobile parts or other articles, of varied sizes and shapes.

10 In its more detailed nature, the invention seeks to provide in hoists of the type referred to, improved adjustable means for engaging the parts to be lifted to adapt the same for lifting automobiles of various axle heights or chassis widths.

With the above and other objects in view that will hereinafter appear, the invention further resides in the novel details of construction, combination and arrangement of 20 parts, all of which will be first fully described, then be particularly pointed out in the appended claims, reference being had to the accompanying drawings, in which:

Figure 1 is a face view illustrating the invention in use.

Figure 2 is an edge view of the parts shown in Figure 1.

Figure 3 is a detail perspective view of the lifting brace and bearing forming member.

30 Figure 4 is a detail perspective view of the derrick arm and mounting post separated.

Figure 5 is a fragmentary face view illustrating one of the laterally adjustable supporting members.

35 Figure 6 is a detail perspective view illustrating one of the adjustable supporting members, per se.

In the drawings, 1 indicates the base of my improved hoist to which are secured the channel iron side standards 2 in which the slide channels or standards 3 are adapted to be 40 vertically guided.

The base 1 and standards 2 and any suitable brace for holding these parts rigid in the relation shown, together with the lifting and lowering devices later to be described, 45 constitute a stationary unit. The slide standards 3 and the cross brace or platform 4 carried thereby and suitably braced as at 5 constitute a lifting unit.

The lifting head 6, carried at the upper end of a plunger 7, moved by the piston 8 and operable in the cylinder 9, is secured to

the cross member 4 through the top 10 of which cylinder the said plunger 7 projects. 55

A suitable fluid duct 11 is provided for admitting fluid under pressure in the cylinder 9 to engage the piston 8 and control lifting and lowering movement of the plunger 7 and head 6. Thus the piston may be said 60 to be part of the stationary unit hereinbefore referred to and the head 6 and plunger and piston 7—8 may be said to constitute a part of the lifting unit hereinbefore referred to.

In carrying out the means embodying my 65 present invention I provide an inverted U-shaped brace member 12, the mounting arms 13 of which are removably insertable in sockets 14 formed in the upper ends of the slide standards 3. The said arms are each 70 provided with a plurality of adjustment holes 15 adapted to receive securing pins 16 insertable through selected ones of the holes and adapted to engage the upper ends of the standards 3 to secure the member 12 at vertically adjusted positions relatively to the 75 said standards.

The member 12 may be equipped with any suitable anti-slip devices, if desired, to facilitate its engagement with an automobile axle 80 for the purpose of elevating the same from a garage floor in association with which the device is mounted.

In the preferred embodiment of the invention the member 12 also includes a central 85 bearing aperture 17 to slidably receive the derrick post 18 equipped with a socket 19 at its lower end for rotatably seating upon the upwardly projecting pin 20 carried by the head 6 of plunger 7 to cause the said post 90 18 to reciprocate vertically with the said plunger 7 guided by the said bearing aperture 17.

At its upper extremity the post 18 has secured thereto, through the medium of the 95 pin and slot connection 21, a removable derrick arm 22 provided with a diagonal brace 23 having a socket rest 24 at its lower end adapted to bear against the said post 18.

As thus far described, the invention may 100 be used without the derrick arrangement merely by elevating the lifting unit to bring the brace member 12 into lifting engagement with the axle or other suitable parts of the vehicle to be lifted or the derrick may be 105 mounted as illustrated in Figure 1, and by

reason of its chain and hook connection 25 connected with any article to be lifted, the manner of extending the derrick arm and the rotatable mounting of the derrick post greatly facilitating such use.

It frequently happens that it is desired to utilize my improved hoist in lifting automobiles or other articles of various widths. To facilitate the lifting of automobiles having 10 various chassis dimensions I provide a pair of laterally adjustable support members 26 laterally adjustably mounted as at 27 on brackets 28 removably insertable into the sockets 14 with which the slide standards 3 are provided. By reason of mounting the supports 26 by bolt and slot arrangement 27 provision is made not only for adjusting the said supports laterally but also for reversing their direction of projection, thus making 20 it possible to adjust the same inwardly or outwardly of the mounting brackets according to the direction in which the same are turned on their connection 27.

Like the arms of the member 12 the brackets 28 may be pin and slot equipped as at 29 for vertical adjustment in the sockets 14 if it be so desired.

Also, if desired, the lifting unit standards 3 may be provided with a plurality of spaced 30 holes 30 to receive a support pin 31 insertable into a selected one of said holes and adapted to bear upon the upper end of the standard 2 at the respective side to support the lifting unit, or secure it to its lifted adjustment, 35 after the manner in which the brace member 12 is supported adjustably upon the said lifting unit, see Figure 3.

While I have disclosed a derrick arrangement herein, I lay no claim thereto in this 40 application as the derrick arrangement constitutes the subject matter of my application filed Sept. 15, 1927, Serial No. 219,641.

From the foregoing description, taken in connection with the accompanying drawings, 45 it is thought that the novel details of construction, the manner of use and the advantages of my invention will be readily apparent to those skilled in the art to which it relates.

50 What I claim is:

1. In a device of the class described where-
in is provided a stationary unit including
vertical guide standards, and a vertically
movable lifting unit including vertical slide
55 standards guided by the guide standards,
and means to lift and lower said lifting unit;

said lifting unit slide standards having sockets in their upper ends, a U-shaped axle engag-
ing member having portions adapted to be
removably received in said standard sockets, 60
and means to vertically adjust the position
of said member.

2. In a device of the class described where-
in is provided a stationary unit including
vertical guide standards, and a vertically 65
movable lifting unit including vertical slide
standards guided by the guide standards, and
means to lift and lower said lifting unit;
said lifting unit slide standards having sockets
in their upper ends, an inverted U-shaped 70
axle engaging member having its side arms
adapted to be removably received in said
standard sockets with its cross portion pro-
jecting upwardly to engage an axle of an
automobile to be lifted, said member having 75
a plurality of pin receiving holes in the
socket received arms thereof and pins insert-
able through selected ones of the holes to
engage the tops of the socketed standards and
secure the member to adjusted positions. 80

3. In a device of the class described, a pair
of stationary vertical guide standards, a pair
of vertically movable bars operating in said
standards, an approximately U-shaped bridge
member having its ends projected into the 85
upper ends of said bars, said bridge mem-
ber extending across the space between adja-
cent standards, means for bracing said stand-
ards, and slide means cooperating with said
bars for effecting the elevation and lowering 90
of said bars, said bars having pin holes and
safety pins adapted to be passed through said
pin holes for the purpose specified.

4. In a device of the class described, a pair
of stationary vertical guide standards, a pair
of vertically movable bars operating in said
standards, an approximately U-shaped bridge
member having its ends projected into the
upper ends of said bars, said bridge mem-
ber extending across the space between adja-
cent standards, means for bracing said 100
standards, and slide means cooperating with
said bars for effecting the elevation and low-
ering of said bars, said bars having pin holes
and safety pins adapted to be passed through
said pin holes, said bridge having its ends re-
movably socketed into the upper ends of said
bars and having its ends also provided with
pin holes, and pins adapted to be received by
said pin holes for the purpose specified. 105

EDWARD ADAM THIELEN.
